UNITED STATES PATENT OFFICE.

CALVIN C. GRINER, OF MACUNGIE, PENNSYLVANIA.

SHOE-CLEANING AND BLACKENING DEVICE.

No. 856,863.

Specification of Letters Patent.

Patented June 11, 1907.

Application filed May 18, 1906. Serial No. 317,577.

To all whom it may concern:

Be it known that I, CALVIN C. GRINER, a citizen of the United States, residing at Macungie, in the county of Lehigh and State of Pennsylvania, have invented certain new and useful Improvements in Shoe Cleaning and Blackening Devices; and I do hereby declare the following to be a full, clear, and exact description of the invention, such as will enable others skilled in the art to which it appertains to make and use the same.

This invention relates to improvements in shoe cleaning and blackening devices, and more particularly to devices for applying liquid polish to shoes.

The invention comprises the production of a blacking distributing means formed with a sponge receiving portion and means for supplying blacking to the same, and a cap for covering the sponge when not in use.

The object in view is the production of a blackening apparatus that is adapted to distribute blacking to a plurality of shoes and to be fed from a suitable source so as to secure the advantages of a fountain brush.

With this and other objects in view, the invention comprises certain novel constructions, combinations and arrangements of parts, as will be hereinafter fully described and claimed.

In the drawings:—Figure 1 represents a perspective view of a part of a room having secured to the walls thereof an apparatus embodying the features of my invention. Fig. 2 is a vertical section through a blacking distributing means embodying the features of my invention.

In the manufacture of shoes it is necessary after the same has been completed to coat the shoes with some kind of blacking and many devices have been provided for accomplishing this result with more or less success.

It is among the objects of the present invention to provide a device that will be continuously supplied with blacking and that will be so arranged as when not in use to be sealed comparatively air-tight to prevent the blacking fluid from evaporating or hardening.

In the preferred embodiment of my invention I provide a suitable tank as 1, in which is placed any desired kind of blacking. The tank 1 may be placed at any convenient point, preferably a considerable distance above the place where the shoes or other articles are to be operated upon, so that suffi-

cient pressure may be given to the fluid to supply the same as rapidly as desired through a suitable tube 2. The tank 1 is provided with a valve, as 3, which is used to shut off the supply of blacking when the device is not being used.

Connected to the valve 3 is a suitable hose or pipe 2, preferably of thin rubber so as to be light in weight and adapted to be moved about with little inconvenience. The pipe 65 or tube 2 may be of any convenient length and simply permitted to lie upon the floor or, as shown in Fig. 1, placed upon hooks, as 4. Connected to the end of the tube 2 is a blacking distributing device 5. The blacking distributing device 5 is preferably made up of a handle-shaped portion 6 through which a suitable aperture or passage 7 is provided. At one end of the handle portion 6 is provided a reduced portion 8 upon which 70 is secured the tube 2. At the end opposite the reduced portion 8 is provided a hollowed out portion, as 9, and a threaded portion, as 10. Secured to the handle portion 6 is a sponge receiving portion 11. The sponge 80 receiving portion 11 is provided with a hollowed out portion, as 12, in which is positioned a sponge, as 13, which projects a suitable distance beyond the end of portion 11 so as to readily impinge against shoes or the 85 like upon which the same is used. The portion 11 has a reduced threaded portion, as 14, which fits into the threaded portion 10 of the handle 6, and is provided with an aperture 15 communicating at one end with 90 the hollowed out portion 12 and at the other with apertures 16 and 17. Formed upon the end of the threaded portion 14 is a reduced portion 18 which is positioned directly opposite the opening or passage-way 7 so that 95 liquid passing through the passage-way 7 will impinge against the portion 18 and be compelled to travel around the same, and finally escape through the passage-ways 16 and 17. The sponge 13 is preferably held in 100 place by a suitable pin, as 19, which passes entirely through the portion 11.

The portion 11 is threaded at 20 for receiving a threaded cap 21. The threaded cap 21 is hollowed out, as at 22, so as to form 105 ample space for accommodating the end of the sponge 13. The cap 21 is adapted to be placed upon the portion 11 so as to cover the sponge 13 and prevent the atmosphere from absorbing the liquid therefrom and conse- 110

2
quently preventing the blacking contained in the sponge from hardening forming a crust on the outer surface thereof.

In operation, when it is desired to use the device, the valve 3 is turned on and the liquid is permitted to pass from the tank 1 through the pipe 2, through the passageways in the distributing device 5, until the same reaches the sponge. The sponge will absorb a considerable amount and hold the same, and also will prevent any more liquid from passing through the pipe 2 until some has been removed from the sponge. After the sponge has thus been saturated the same is ready to be applied to shoes or anything else that it is desired to be coated with the liquid. The cap 21 is then removed and the distributing device 5 is moved over the device to be blackened, the sponge 13 impinging against the same and distributing liquid evenly over the surface thereof. By thus having a constant supply of blacking for the sponge 13 an even coating is given to the shoe or other device being blackened. This is not possible where the blacking distributing device is placed in a blacking fluid and then removed to be applied to the shoe. In this instance, where the blacking distributing device is first applied receives the majority of the blacking where the last place probably receives a considerable less amount. As will be evident my improved device will furnish an even coating over the entire surface of the shoe.

I have described my device as particularly adapted to the use of blackening shoes and also in the blackening of shoes after the manufacture, but it will be understood that

I consider it within the scope of this invention to use the device in blackening shoes 40 any time and at any place. It is also within the scope of the invention to use the device for coating other things as well as shoes.

Having thus fully described my invention, what I claim and desire to secure by Letters 45 Patent, is:—

1. In a device of the class described, a handle having a longitudinal bore, and with a socket formed in the end and in communication with the bore, a sleeve inserted within and having passages communicating with the socket, a pervious material within the sleeve, means to maintain the pervious material in position, a tube communicating with the bore of the handle, and means adapted 55 to supply a fluid to the tube.

2. In a device of the class described, a handle having a longitudinal bore, and with a socket formed in the end and in communication with the bore, a sleeve inserted within 60 but not filling the socket, and having passages communicating therewith, a pervious material within the sleeve, a pin inserted through the sleeve and adapted to maintain the pervious material in position, a tube 65 communicating with the bore of the handle, means adapted to supply a fluid to the tube, and a closure proportioned to embrace the sleeve and the pervious material.

In testimony whereof I affix my signature 70 in presence of two witnesses.

CALVIN C. GRINER.
